H. G. MARTIN,
PORTABLE ELECTRIC LIGHT,
APPLICATION FILED FEB. 2, 1918.

1,318,400.

Patented Oct. 14, 1919.

Horace G. Martin, Inventor

By his Attorney
Murray Cornington.

UNITED STATES PATENT OFFICE.

HORACE G. MARTIN, OF RUTHERFORD, NEW JERSEY.

PORTABLE ELECTRIC LIGHT.

1,318,400.

Specification of Letters Patent.

Patented Oct. 14, 1919.

Application filed February 2, 1918. Serial No. 215,056.

To all whom it may concern:

Be it known that I, HORACE G. MARTIN, a citizen of the United States, residing at Rutherford, in the county of Bergen, State 5 of New Jersey, have invented a new and useful Improvement in Portable Electric Lights, of which the following is a specification.

My invention relates to improvements in 10 portable electric lights. Referring to the drawings, Figure 1 is a front elevation of an apparatus embodying my invention; Fig. 2 is a side elevation of the same, looking toward the left in Fig. 1; Fig. 3 is a sectional 15 view somewhat enlarged of the upper portion of the apparatus of Fig. 2.

In the drawings, 1 is a dry battery cell having poles 2 and 3. A main connector piece, 4, which may serve both as a conductor and as a handle or support 4^a for carrying the apparatus, is secured to pole 2 by a nut 5, and another connector or conductor, 6, is secured to pole 3 by a nut 7. An electric lamp 8, with a suitable bulb 8^a 25 and reflector 9, is secured to a metal piece or holder 10, so arranged that it serves as a spring to hold the lamp in electrical contact with main connector 4 at the point 8^b, Fig. 3. A switch 11 is fastened to the metal 30 piece or lamp holder 10 by suitable means, such as a rivet 12. The parts 4, 6 and 10 are secured together by two bolts 13 and 14, but so as to be insulated from one another. As shown particularly in Fig. 3, insulated pieces 15 and 16 are placed between 35 the metal parts 4, 6 and 4, 10, respectively, with cylinders of insulation through which bolts 13 and 14 are inserted, with the result that metal pieces 4, 6 and 10 are held firmly 40 together but insulated from one another.

Switch 11 is in electrical contact with lamp holder 10 and thence through lamp 8, point 8^b and main connector 4 with pole 2 of cell 1. Bolt 13 is in electrical contact 45 with piece 6 and pole 3 of cell 1. When, therefore, switch 11, which is in position to be readily moved between the thumb and finger of the hand holding connector 4 at its horizontal portion 4^a, Fig. 2, is moved 50 into contact with bolt 13, Fig. 3, a circuit is established, otherwise the circuit is open.

The operation of the device is very simple. In Figs. 1 and 2 switch 11 is open, the circuit is broken and no light issues from the 55 apparatus. When switch 11 is turned so as

to bear against bolt 13, as shown in Fig. 3, the circuit through the dry cell 1 and the lamp 8 is closed and the current flows from pole 2 of cell 1 through parts 4, 8^b, lamp 8, holder piece 10, rivet 12, switch 11, bolt 13 60 and the connector 6 to pole 3 of the dry cell. By moving switch 11 to close and open the circuit the lamp 8 may be illuminated or darkened at pleasure. It will be seen that the connections may be made directly to 65 the poles of the battery without any intermediate wiring, thus simplifying and cheapening construction, increasing efficiency, etc.

I claim:

1. In an electric light, the combination 70 of a battery cell, two metal connector pieces secured one to each pole of said cell, a holder piece for an electric lamp, insulation pieces for keeping said connector and holder pieces out of electric contact with one another, 75 means for securing said connector and holder and said insulation pieces together, an electric lamp secured to said holder piece and having its two elements in electric contact with said holder piece and one of said 80 connector pieces, respectively, and a switch secured to said holder piece and arranged to be moved to make and break electric contact with the other of said connector pieces.

2. In an electric light, the combination 85 of a battery cell, two metal connectors secured one to each pole of said cell, a holder piece of spring material for an electric lamp, insulation pieces for keeping said connector and holder pieces out of electric contact with 90 one another, means for securing said connector and holder pieces and said insulation pieces together, an electric lamp secured to said holder piece with one of its elements in contact therewith and having its other 95 element held in contact with one of said connector pieces by the tension of said holder piece, a switch secured to said holder piece and arranged to be moved to make and break electrical contact with the other of 100 said connector pieces.

3. In an electric light, the combination 105 of a battery cell, a connector piece having one of its ends secured to one pole of said cell and its other end free and shaped into a handle for carrying said apparatus, a second connector piece connected to the other pole of said cell, a holder piece for an electric lamp, insulation pieces for keeping said connector and holder pieces out of electrical 110

contact with one another, means for securing said connector and holder pieces and said insulation pieces together, an electric lamp secured to said holder piece and having its elements in contact with said holder piece and one of said connector pieces, respectively, and a switch connected to said

holder piece and adapted to be alternately moved by the thumb and forefinger of the hand while holding said handle to open and close electrical contact between said holder piece and the other of said connector pieces.

HORACE G. MARTIN.

Copies of this patent may be obtained for five cents each, by addressing the "Commissioner of Patents, Washington, D. C."
